UNITED STATES PATENT OFFICE.

GEORGE P. REINTJES, OF KANSAS CITY, MISSOURI.

CORNER-FILL FURNACE-WALL CONSTRUCTION.

Application filed October 18, 1926. Serial No. 142,858.

This invention relates to furnace wall construction, and more especially to a construction for filling the reentrant angles of the corners of such furnaces, in which corners 5 of the ordinary type of furnaces, gases and the like, form eddies and so interfere with the circulation in the combustion chamber of the furnace as to impair the efficiency of the latter. My object therefore is to provide 10 a corner-fill tile construction to eliminate such dead or gas-eddying chambers, and which while providing a perfect bonding of the fill with the furnace walls, is susceptible of ready and economical repair by replacement of the filling tile rendered defective by 15 burning or otherwise.

With this general object in view, the invention consists in the novel combination and arrangement of parts as hereinafter described and claimed; and in order that it 20 may be fully understood reference is to be had to the accompanying drawing, in which:

Figure 1 is a fragmentary perspective view of a corner of a furnace provided with 25 filling tiles arranged in accordance with the invention.

Figure 2 is a plan view of the same.

Figure 3 is a similar view but showing the horizontal wall and filling tile course next 30 below or above the course appearing in Figure 2.

Figure 4 is a horizontal section of a corner of a furnace equipped with corner filling tiles of a slightly modified construction, 35 the modification consisting primarily in making each corner tile in one piece instead of in two pieces as illustrated by Figures 1 to 3 inclusive.

Figure 5 is a detail perspective view of a 40 corner filling tile corresponding to that shown by Figure 4, but showing the inner end of the tile concaved instead of straight, to provide for a rounded corner fill, as indicated by the curved dotted line in Figure 4.

Referring to the drawing, 1 and 2 indicate intersecting walls forming a corner of a furnace or the like, the walls being composed entirely, if desired, of ordinary fire brick or tile, though it is preferred to use for the extreme corner pieces of the walls, tiles of the character and arrangement shown and described in my Patent No. 1,586,841, dated June 1, 1926, the corner tiles of the character mentioned being identified by the reference 55 characters 3 and 4, and of the same thick-

ness as the respective courses of the brick-work.

For the purpose of filling the reentrant angle formed by said intersecting walls, two sets of refractory tiles are employed, each 60 set projecting inwardly from its respective wall and parallel with the other wall, and the sets of the respective walls are arranged at their inner ends in superposed overlapping relation so as to provide a solid filling 65 for the reentrant angle into which they project. The inner ends of the filling tiles,—which are of identical construction,—extend angularly with respect to their outer ends, and the filling tiles of the two walls are so 70 related or arranged that the inner ends of all of them are flush and form a solid face extending diagonally from the inner face of one wall to the inner face of the other, thereby avoiding the production of a dead air 75 space in the corner where gases and the like may eddy, and providing for a complete and unimpaired circulation of gases within the combustion chamber of the furnace.

In the construction shown most clearly by 80 Figures 1 to 3 inclusive, the filling tile of one wall consists of two similar tile sections 5 and 6, and the corresponding tile members of the other wall are identified by the characters 7 and 8. The tile courses 5—6 and 85 7—8 are arranged in alternate courses of their respective walls and in different horizontal planes so that within the walls they stand in overlapping relation. The tile sections 5 and 7 of the two walls, are bonded 90 with their respective walls by being set therein. The tile sections 6 and 8 are interposed between the inner ends of the tiles 5 and 7 of their respective walls and the corresponding brickwork course of the other 95 walls, each tile 6 and the corresponding tile 8 being bonded between the tiles 5 and 7 respectively and the other wall. The inner ends of the tiles are correspondingly angled and when arranged as desired all stand in the same vertical plane at an angle of 45° to the walls, and hence lying flush with each other form a solid or unbroken face extending across the corner of the furnace from one intersecting wall to the other.

The construction shown in Figures 1 to 3 inclusive, is preferred if the corners of the furnace wall are composed of tiles of the type indicated by reference characters 3 and 4. If the furnace is built wholly of 100

- brick or tile of conventional type, filling tiles of the type 5—6 and 7—8 may be employed, or corresponding tiles may be used of one-piece construction, that is to say, in 5 each wall respectively, there may be alternately overlapping tiles 9 and 10, which each correspond in width to two of the tiles 5—6 or 7—8, the inner bevelled end of each tile 9—10, being of sufficient length to extend 10 from one wall to the other, or the inner ends of such tiles instead of being bevelled as shown by full lines, Figure 4, may be concaved as indicated at 11 so as to provide a rounded instead of a straight corner fill. 15 In the one-piece construction also the outer end of each tile may be straight for its full width, whereas in the construction shown by Figures 1 to 3 inclusive, the use of two identical tiles 5—6 or 7—8 with one of each 20 set setting further inward than the other leaves a notch or recess 12 for the accommodation of the inner portions 13 of the tiles 3 and 4. Where such corner tiles 3 and 4, are not employed, as contemplated where an all 25 brickwork wall is used, as suggested by Figure 4, no notch of the character mentioned is needed.

From the foregoing, it will be apparent that I have produced a corner fill construction which permits of the ready repair or replacement thereof without disturbing the walls and which is of simple and economical construction, and it is to be understood that I reserve the right to make any changes in 30 the form and arrangement of the filling tiles falling within the spirit and scope of the appended claims.

I claim:

1. The combination with intersecting walls 40 composed of conventional brickwork courses, of two sets of corner filling tiles, one set bonding with each wall and projecting inwardly thereof, the tiles of the filling courses corresponding in thickness to the 45 elements of the brickwork courses; each filling tile set bearing an overlapping relation where inward of the respective wall, with the corresponding portion of the filling tiles of the next lower course of the 50 other wall.
2. The combination with intersecting walls 55 composed of conventional brickwork courses, of two sets of corner filling tiles, one set bonding with each wall and projecting inwardly thereof, the tiles of the filling courses

corresponding in thickness to the elements of the brickwork courses; each filling tile set bearing an overlapping relation where inward of the respective wall, with the corresponding portion of the filling tiles of the 60 next lower course of the other wall; the inner ends of the filling tiles of the two walls extending across the reentrant angle formed by the walls.

3. The combination with intersecting walls 65 composed of conventional brickwork courses, of two sets of corner filling tiles, one set bonding with each wall and projecting inwardly thereof, the tiles of the filling courses corresponding in thickness to the 70 elements of the brickwork courses; each filling tile set bearing an overlapping relation where inward of the respective wall, with the corresponding portion of the filling tiles of the next lower course of the other wall; 75 the inner ends of the filling tiles of the two walls extending across the reentrant angle formed by the walls and occupying the same vertical plane to provide a smooth or unbroken surface. 80

4. The combination with intersecting walls composed of horizontal brick or tile courses, of two sets of corner filling tiles, each set consisting of a plurality of courses composed of two similar tiles extending 85 parallel with the wall of the other set and arranged in sidewise abutting relation, the courses of tiles being in the same horizontal plane as alternate courses of the brickwork of the respective walls, the inner ends of the 90 abutting tiles of one set being flush with each other and the corresponding ends of the abutting tiles of the other set, all of such ends conjointly providing a smooth, solid face or wall extending from one of the 95 furnace walls to the other across the reentrant angle formed thereby.

5. The combination with intersecting walls composed of refractory material courses, of two sets of corner filling tiles, 100 one set bonding with each wall and projecting inwardly thereof; each filling tile set bearing an overlapping relation inward of its respective wall, with a corresponding portion of the filling tiles of the next lower 105 course of the other wall.

In witness whereof I hereunto affix my signature.

GEORGE P. REINTJES.
